UNITED STATES PATENT OFFICE.

SAM B. THOMPSON, OF NORFOLK, VIRGINIA, ASSIGNOR OF ONE-FIFTH TO
CHARLES E. ROPER AND EDWIN R. ABBOTT, OF SAME PLACE.

FOLDING CRATE.

SPECIFICATION forming part of Letters Patent No. 623,849, dated April 25, 1899.

Application filed June 21, 1898. Serial No. 684,055. (No model.)

To all whom it may concern:

Be it known that I, SAM B. THOMPSON, a subject of the Queen of Great Britain, residing at Norfolk, in the county of Norfolk and State 5 of Virginia, have invented certain new and useful Improvements in Folding Crates; and I do hereby declare the following to be a full, clear, and exact description of the invention, such as will enable others skilled in the art to 10 to which it appertains to make and use the same.

My invention relates to folding crates for containing poultry or produce.

The object of the present invention is the provision of an improved crate of simple and 15 inexpensive construction which will be strong, rigid, and commodious when extended and adapted for rapid and easy extension or for folding into extremely-compact and readily-portable form, so as to occupy but little space 20 when not in use or while being reshipped.

The invention is embodied in a crate whose component parts are of improved construction and connected together in a novel manner for folding and extension, as more fully 25 set forth in the following description and claims.

In the accompanying drawings, Figure 1 is a perspective view of my complete crate when in extended arrangement, certain parts being 30 broken away to better disclose the construction; Fig. 2, a perspective view of the crate when folded, parts being broken away to show the position of the folded sides; Fig. 3, a detail view of one of the hinge connections, and Fig. 4 a detail view of another 35 hinge connection.

The crate-bottom 1 is, as usual, of rectangular shape and is provided at one end with a raised transverse piece 2. A rectangular 40 frame 3 of the same size as the bottom is supported above the latter by standards 4, preferably of steel, which are pivoted at the points 5 and 6 to the bottom 1 and frame 3, respectively. Any suitable pivotal connection can 45 be employed; but I prefer to use split rivets, which are clenched on the inside of the frame. As many of the standards can be employed as found desirable; but three on each side, disposed at the ends and center of the crate,

as shown, are usually sufficient. The top 50 frame 3 has a rabbet 7 for the reception of a top or cover 8, which is hinged to the frame and lies flush with it when closed. The sides, which are shown at 9, have their lower edges connected to the bottom by staple-hinges 10 55 and are located next the inner faces of the standards and adapted to fold down flat on the bottom of the crate. These sides are just high enough to fit in snugly yet easily under the frame 3 when the latter is raised and the 60 standards are disposed vertically, and they act as supports and braces for said frame and assist in maintaining it rigid when extended. A suitable number of gravity catch-pins 11, which pass through the frame 3 and into the 65 upper portions of the sides, securely hold the sides in position. The sides, it will be observed, lie flush or somewhat below the piece 2 when they are folded against the bottom 1. The ends are shown at 12 and 13, the upper 70 edge of end 12 being rounded at 14, adjacent the end of the frame 3, to prevent binding and the lower edge of end 13 being similarly rounded for a like purpose adjacent the end of the bottom 1.

Duplicate metallic hinge-plates 14 are secured to and project beyond the side pieces of the frame 3, at one end thereof, said plates being provided with horizontal slots 15, terminating in enlargements 16, said slots and 80 enlargements loosely receiving the shanks of screws 17, (a single bolt could be substituted, if desired,) which are entered in the end 12. The lower portion of end 13 is attached to the bottom 1 by a hinge connection similar to 85 that just described. The end standards are notched or grooved at 21 to permit the free movement of the heads of the screws 17 when folding or extending the crate.

Ordinary hinges can be employed for connecting the lower edge of end 12 to the piece 2 and the upper edge of end 13 to the frame 3, if desired; but I prefer to use the following improved hinge connection because of its cheapness and advantages: The numerals 18 90 95 designate metallic hinge members of substantially the shape of a figure 3, which have their ends entered and secured in the bottom

1 and piece 2 and their intermediate portions free or disposed away from the same. Staples 19 on the lower edge of the end 12 encircle and are adapted to slide on the hinge members, but their movement in one direction is limited by the humps or stops 20 of said members. The top portion of end 13 has staples 19, which are engaged with hinge members 18 on the frame 3, similar to those just described. The humps are so disposed that by their engagement with the staples when the crate is extended they prevent any longitudinal shifting or displacement of the ends should the crate be subjected to a pressure which would tend to cause such displacement. These hinge members can be cheaply and easily stamped from sheet metal and, together with the staples, constitute a cheap and strong connection.

20 The bottom is preferably made solid, but the ends, sides, and top are covered with wire-netting for purposes of ventilation, although they may be constructed solid or even provided with glass. The crate can be used for 25 any of the purposes to which crates are usually subjected, but when used for poultry it is desirable to provide each side with a small hinged door 22, one only being shown in the drawings, for the sake of convenience in handling the contents of the crate. The top or cover is used in removing produce from the crate.

If the crate is extended and it is desired to fold it, this is accomplished in the following 35 manner: The catch-pins 11 are lifted and the sides upon being pushed inward fall flat on the bottom. When the top frame and ends are folded down on the sides, the crate is completely collapsed and is then in a flat and 40 very compact form, so that it occupies but little space. These operations and the reverse of them can be accomplished very rapidly and easily.

Owing to the relative disposition of the pivotal or hinge points of the standards and ends the latter during folding or extension of the crate move in a manner eccentric to each other; but this is compensated for by the slots 15 and enlargements 16, which permit the necessary movements of the screws 45 17. During the movement of the ends the staples 19 slide on the curved portions of the hinge members 18. The transverse piece 2, being as high as the sides when the latter are 50 folded on the bottom, insures the perfectly flat folding of the top and ends, and thus permits of piling or stacking a number of the crates on top of each other, so that they can be stored or shipped in systematic and regular order. The construction of my crate can be varied in many particulars without detracting from any of its advantages or departing from the spirit and scope of the invention, and I do not, therefore, limit myself to 60 the specific construction herein shown and

described, but consider myself entitled to all variations or modifications falling fairly within the spirit of the invention.

Having thus described my invention, what I claim as new, and desire to secure by Letters 7c Patent, is—

1. In a folding crate, the combination with a bottom, of a foldable top, sides, ends, a hinge connection between the bottom and one of the ends which consists of slotted plates connected to the bottom and hinge-pivots on the end which are loosely received in the slots, a similar hinge connection between the other end and the top, and additional hinge connections between the first-named end and the top and the last-named end and the bottom. 75

2. In a folding crate, the combination with a bottom, of a foldable top, sides, and ends which are hinged to the bottom and to the top, one hinge connection of each end consisting of hinge members having humps or stops, and eyes interlocked with and slideable on the hinge members. 85

3. In a folding crate, the combination with a bottom, of a foldable top, sides, and ends, one of which is hinged to the bottom and the other to the top, and connections between the other portions of the ends and the top and bottom, respectively, which consist of hinge members of substantially the shape of a figure 95 "3" which have their ends fastened and their intermediate portions free, and eyes which are interlocked with and slideable on said members. 90

4. A folding crate, comprising a bottom, a 100 foldable top, sides, and ends which are hinged to the top and bottom, one hinge connection for each end having a shiftable pivot, and the other hinge connection for each end consisting of a hinge member having a hump or stop, 105 and an eye interlocked with the member and slideable on it.

5. A folding crate, comprising a bottom, a foldable top, sides, and ends which are hinged to the top and bottom, one of said hinge connections consisting of slotted plates and pivots movable in said slots, and the other hinge connection comprising hinge members having their ends secured and their intermediate portions free and provided with humps or stops, 115 and eyes interlocked with, and slideable on, the members. 110

6. A folding crate, comprising a bottom, a top, standards pivoted to the top and to the bottom, and ends hinged, respectively, to the top and bottom in an eccentric manner in relation to the standards and having one of their said hinge connections provided with a shiftable pivot. 120

7. In a folding crate, the combination with 125 two of the relatively foldable parts thereof, of a permanent hinge composed of a member having a slot provided with an enlargement and connected to one of the movable parts, and a pivot, connected to the other part, said 130

pivot being adapted to travel in the slot and enlargement during the movement of the foldable parts.

8. In a folding crate, the combination with two of the relatively movable parts thereof, of a hinge consisting of a member of substantially the shape of the numeral "8," connected to one of the parts, and an eye interlocked

with, and slideable on, said member, which is connected to the other movable part. ¹⁰

In testimony whereof I affix my signature in presence of two witnesses.

SAM B. THOMPSON.
